METHOD OF MAKING CHAPLETS

Samuel H. Gibson, Lakewood, Ohio, assignor to
The Fanner Manufacturing Company, Cleve-
land, Ohio, a corporation of Ohio

Application January 15, 1932. Serial No. 586,753

4 Claims. (Cl. 164—17)

This invention relates to chaplets for holding cores in place in molds, and has for its object the production of a chaplet, considered both as an article of manufacture and as a method of making, which shall be characterized by strength, simplicity and efficiency in the article, and by simplicity of operation and economy of material in the method of making. One of the features of improvement in the article is the provision of means on the stem of the chaplet whereby the portion of such stem that extends into the casting will be effectively incorporated therewith, as well as means whereby that portion of the chaplet which protrudes from the casting can be readily broken off. Another feature of improvement is the formation of the head in such a way that sand will readily find its way on both sides of the head and readily pack on both sides, thus eliminating the need for tucking the sand about the head. A further object of the method of making is the utilization of material, which would otherwise be waste, for core tins.

To the accomplishment of the foregoing and related ends, said invention, then, consists of the means and steps hereinafter fully described and particularly pointed out in the claims.

The annexed drawing and the following description set forth in detail certain means and one mode of carrying out the invention, such 30 disclosed means and mode illustrating, however, but one of various ways in which the principle of the invention may be used.

In the drawing:

Figs. 1 and 2 are respectively a perspective view, 35 and a side view partly in elevation and partly in section of one form of chaplet embodying my present improvements; Figs. 3 and 4 are views similar to Figs. 1 and 2, but showing a modification; Fig. 5 illustrates the steps in forming the head of the chaplet of Fig. 1; and Fig. 6 similarly illustrates the steps in forming such modified chaplet head.

Referring now particularly to Figs. 1 and 5, the base or head portion 1 of this form of chaplet 45 comprises a flat piece of sheet metal resembling a Maltese cross, having four arms such as 2 pointed as at 3 by the intersection of the outer cutting lines 4 and 5 of the blank as shown in Fig. 5. Each two adjacent arms have what may 50 be termed a common side 8, preferably of semi-circular shape. The shank or stem 9 is seated in a central opening 10 and upset above and below the head 1 as shown at 11 and 12 to maintain a firm position with respect to the head. At a distance from the upper end of the stem equal to

the thickness of the expected casting, the stem is deeply indented at both sides as at 15, and a collar 16 is upset just above these indentations to serve as locating means. Above this collar, in the portion of the stem which will remain in the 60 casing, notches 17 are formed, preferably by indentations, to insure firm engagement of the cast metal with the stem.

The modification shown in Figs. 3 and 4 includes a base or head 21, which may be of any convenient 65 form, but is here shown as a Latin cross with pointed ends. A stem 22 is secured to the center of the base by suitable means such as upsets 23 and 24. The stem 22 is relieved, or indented, as at 25 for breaking at the surface of the casting, 70 and is surrounded by a collar 26 just above 25. For a short distance above the collar 26 the stem continues at full diameter and then is reduced as shown at 27 up to slightly below the top 28, which is again of full diameter. Thus shoulders are left 75 at each end of the reduced portion, and this arrangement gives a firm engagement of the stem in the metal of the casting.

In forming the various upsets, indentations and notches, any suitable machinery of well known 80 type may be employed and these operations therefore need not be described for the present purpose. However, for forming a head such as that shown in Figs. 1 and 5, or the modified form shown in Fig. 6, I prefer to use a flat strip of metal 85 such as 30 or 31 and to feed the same through a press which at one operation will punch three holes such as 32 and 33 in triangular arrangement and a smaller opening 10. These successive 90 punching steps result in what may be described as a diamond-shaped series of holes in which the holes 32 which form two points of each diamond are adjacent the respective edges of the strip 30 and the holes 33 those which form the other two points are longitudinally disposed along the 95 center of the strip. Each one of the series 33 is common to two of the diamonds. The small holes 10 are on the center line of the holes 33, midway between each pair. At the end of the strip 30 the blank for each chaplet head 1 is severed 100 squarely across the strip along the line 35 in prolongation of the diameter of one of the holes 33. The sides 36 are similarly cut off along the lines 37, parallel to the sides of the strip, thus leaving the formed head 1. The punchings from the 105 various holes 32, 33 are indicated in general at 38. These form core tins, which are commercial articles of foundry supply. Thus it will be seen that there is no waste in the formation of the chaplet head except the side pieces 36. The re- 110

moval of material at 32 forms the side openings 8 leaving the head 1 in a shape that combines a sufficient bearing surface with a minimum blocking effect upon the packing of sand under the head. Thus the extension of the arms 2 gives a firm bearing on the sand, but the openings 8 permit sand to get in against both faces of the arms so that tucking is not required.

In making the heads shown in Fig. 3 the method is the same as just described, and is illustrated in Fig. 6. This needs no explanation beyond calling attention to the fact that the resulting core tins 39 are square.

It will be understood that the exact form of heads shown in Figs. 1 and 3 is not essential and that the principle of this invention, both as to article and method, may be applied to various other suitable forms of heads.

From the foregoing it will be seen that I have produced a simple and efficient chaplet combining a maximum of bearing surface with a minimum of resistance to packing or "tucking" of the sand about the head and that I have devised a method of manufacturing the heads which results in high efficiency in the use of metal.

Other forms may be employed embodying the features of my invention instead of the one here explained, change being made in the form or construction, provided the elements stated by any of the following claims or the equivalent of such stated elements be employed, whether produced by my preferred method or by others embodying steps equivalent to those stated in the following claims.

I therefore particularly point out and distinctly claim as my invention:

1. A method of making chaplet heads and core tins which comprises punching from a strip of metal circular disks at longitudinal intervals in three rows, two of said rows being along the respective edges and one down the center, the edge punchings being transversely aligned, and the center punchings being intermediate of the edge punchings, then trimming the edges longitudinally through the diameters of the edge holes, and severing the remaining central strip transversely through the diameter of each hole of the central row.

2. A method of making chaplet heads which includes punching blanks from a strip and cutting said strip longitudinally to intersect some of the openings formed by said punching operation and transversely to intersect others of said openings.

3. A method of making chaplet heads which includes punching blanks from a strip thereby leaving relatively narrow divergent connected arms, and severing the ends of said arms, thereby separating the heads from the strip.

4. A method of making chaplet heads which includes punching blanks from a strip in groups of three at an angle of 45° across said strip and cutting through the openings so formed, the cutting through of the middle openings of each group being on lines at 90° across said strip and the cutting through the end openings of each group being on lines longitudinal of the strip.
